UNITED STATES PATENT OFFICE.

GEORGE E. CANFIELD, OF MINNEAPOLIS, MINNESOTA, ASSIGNOR TO JAMES M. DOBSON, OF MINNEAPOLIS, MINNESOTA.

CENTRIFUGAL GOVERNOR FOR FORDSON TRACTORS.

1,393,084.

Specification of Letters Patent. Patented Oct. 11, 1921.

Application filed February 13, 1920. Serial No. 358,521.

To all whom it may concern:

Be it known that I, GEORGE E. CANFIELD, a citizen of the United States, residing at Minneapolis, in the county of Hennepin and 5 State of Minnesota, have invented certain new and useful Improvements in Centrifugal Governors for Fordson Tractors; and I do hereby declare the following to be a full, clear, and exact description of the invention, 10 such as will enable others skilled in the art to which it appertains to make and use the same.

This invention, as well as my pending application S. N. 284,430, filed March 22, 1919, 15 has for its particular object the provision of an improved governor for the well known Fordson tractors, and the present invention is in the nature of a modification or refinement of the earlier form disclosed in the 20 said pending application.

Generally stated, the invention consists of the novel devices and combinations of devices hereinafter described and defined in the claims.

25 In the accompanying drawings which illustrate the invention, like characters indicate like parts throughout the several views.

Referring to the drawings:

Figure 1 is a side elevation with some 30 parts sectioned and some parts broken away, showing the improved governor applied to a Fordson tractor;

Fig. 2 is a plan view of the governor and certain of the connections thereto, some 35 parts being sectioned, and some parts being broken away;

Fig. 3 is a fragmentary view in axial section through that portion of the vapor intake manifold in which the throttle valve is 40 applied, the same being a section approximately on the line 3—3 of Fig. 1;

Fig. 4 is an edge elevation of the duplex throttle valve;

Fig. 5 is a face elevation showing the two 45 parts of the duplex throttle valve separated;

Fig. 6 is a side elevation of the governor, some parts being broken away and some parts being sectioned; and

Fig. 7 is a section on the line 7—7 of 50 Fig. 6.

Of the parts of the Fordson tractor, it is only desirable for the purposes of this case to particularly note the front wheels 8, the radiator 9, the hood 10, the cylinder and 55 crank case castings 11, the fuel intake mani-

fold 12, the exhaust manifold 13 and the engine cam shaft 14. The throttle valve here employed is of a duplex character and is made up of two disks 15 and 16 having notches 15^a and 16^a, respectively, that are 60 adapted to interlap so as to adapt the two sections of the throttle valve to be independently oscillated on the axis indicated by the line y—y in Fig. 5, said axis being coincident with the axes of the projecting 65 shaft shown in Fig. 3. The throttle valve is located in a tubular portion 12^a of the vapor intake manifold 12 and the disk 15 is connected to the inner end of a rearwardly extended oscillatory rod 19, while 70 the disk 16 is connected to the inner end of a forwardly projected oscillating rod 20. The rod 19 will be operated in the customary way by connections that extend to within reach of the operator of the tractor, so that 75 the said disk 15 may be operated as a throttle valve acting in the customary manner, while the disk 16 is left in an open position. Moreover, by oscillations of the rod 20, the disk 16 may be operated as a throttle valve, 80 while the disk 15 is left in an open position. The said rod 20 will be oscillated automatically by my improved governor so that there is provided means for operating the throttle valve either at will or automatically by the 85 governor.

The governor comprises an upright shaft 21 journaled in suitable bearings in the upper and lower portions of a governor casing 22, the latter being preferably a hollow cast 90 shell made up of two parts separably united by a horizontal joint 22 and detachably but rigidly connected together by machine screws 23, or the like. The upper end of the shaft 21 is mounted in a combined bearing and thrust bearing 24 preferably of the ball bearing type and which is seated in a hub portion 25 of the casing 22.

Surrounding the hub 25 and rising above the same, the upper section of the governor 100 casing 22 is formed with an annular flange or cup structure 26 that is adapted to contain oil, but which performs a more important function in that it supports the cap-like shell 27 of the current distributor or timer. The said shell 27 is telescoped onto the reduced upper end of the flange 26 and is yieldingly pressed downward by a spring arm 28 shown as anchored to a lug on a hollow dome-like extension 29 of the upper 105

2

section of the governor casing. The shell 27 supports the relatively stationary contacts 27^a of the current distributor, said contacts being insulated from the shell 27 and having 5 projecting binding posts 30 to which the leads of the ignition circuit will be connected in the customary way. The movable contact member 31 of the distributor is carried by the extreme upper end of the shaft 10 21 and moves over the contacts 27^a in the customary way to produce the sparks in the several cylinders with properly timed actions. By means hereinafter described, the shell 27 may be oscillated slightly in advance or retard the spark.

At its lower end, just above its lower bearing, the shaft 21 is provided with a spiral gear 32 that meshes with a spiral gear 33 on the forwardly projecting end of the engine crank shaft 14, said gear being of such size that the shaft 21 is driven at the same speed as the crank shaft 14.

The governor casing 22, just below its flange 26 is bulged out to afford space and 25 clearance for the two weighted governor arms 34 that are pivoted at 35 to a collar 36 on the shaft 21. The weighted arms 34 are provided at points offset from their pivots with bearing points afforded, as shown, 30 by small anti-friction rollers 34^a that engage a disk-like flange or plate 37 mounted to slide vertically on the shaft 21. Loosely mounted for both rotary and sliding movements on the shaft 21 is a flanged sleeve 38 35 between which and the hub of the plate 37, a ball bearing 39 is interposed so that the said disks 37 may be freely rotated with the shaft 21 and with the weighted levers 34 without causing the flange sleeve 38 to rotate.

The numeral 40 indicates an L-shaped lever that operates much like a bell crank, but which is pivotally connected to internal lugs 41 on the upper section of the casing 45 22 at 42, the said pivot being located between the elbow and the inner extremity of the lower arms of said lever. Here it should be noted that the inner end of the lower arm of the lever 40 is bifurcated or pronged 50 so that it straddles the body of the sleeve 38 and rests upon the flange thereof.

The outer portion of the lever 40 is yieldingly pressed upward by a coiled spring 43 compressed between the elbow thereof and 55 the inner end of an adjusting screw 44 that works with threaded engagement through the offset portion of the casing 22.

At the upper end of its upright arm, the lever 40 is shown as provided with a slot 60 45 that is engaged by the crank pin 46 of a short crank arm 47 secured on the front end of the heretofore noted throttle valve rod 20, the latter, as will now be noted, being extended forward and into the drum 29 of 65 the governor casing.

The numeral 48 indicates a small tube that extends from the bottom of the cup formed within the flange 26 and terminates in position to deliver oil directly onto the ball bearing 39. In Figs. 1 and 2, the numeral 70 49 indicates a small rock shaft that extends forward from the point within reach of the operator, is mounted in suitable bearings 50 on the exterior of the cylinder casting, and at its front end, has a short arm 51, which, 75 by a link 52, is connected to an outstanding lug 53 on the distributor shell 27, so that by oscillation of said shaft 49, the relatively fixed contacts of the distributor may be moved to retard or advance the spark.

As a simple and efficient means of detachably but rigidly securing the governor casing to the crank case of the engine, said casing is provided with offset bosses 54 to which the front ends of threaded studs 55 80 are attached by means of nuts 56; and the rear ends of these studs are preferably applied as substitutes for certain other customary bolts 57 that connect the front end of the crank shaft casing to the body of 85 said crank casing.

The timer connected as above described will be operated so far as its time action is concerned, exactly like the distributor which has hitherto been attached directly to the 90 cam shaft to the engine, but it is raised to an elevated position where it will be protected from mud, dirt, oil, or the like, and hence, less likely to be short circuited.

When the engine is running at slow speed, 100 the weighted governor levers 34 will drop, being acted upon both by gravity and the tension of the spring 43, and lever 40 will then be set in position to hold the throttle valve disk 16 into an open or nearly open 105 position.

When the engine begins to speed up, the weighted levers 34 will be thrown outward by the action of centrifugal force, and acting against the tension of spring 43, will 110 move the upper end of lever 40 toward the left in respect to Fig. 7, and its slotted upper end acts on pin 46 of arms 45, will oscillate rod 47 and cause the latter to move throttle valve disk 16 toward a closed position, and to close the said throttle valve whenever the engine has acquired a certain predetermined desired maximum speed. This predetermined maximum speed of the 115 engine may be varied by adjustments of the tension of the spring 43.

When the speed of the engine is decreased below the predetermined maximum speed, spring 43 will begin to overcome the centrifugal force exerted through levers 34 so 120 that better supply of vapor is afforded and this, of course, tends to again speed up the engine. Thus, the governor acts, irrespective of the work that the engine is doing or the load that it is carrying, to automati- 125 130

cally maintain a constant speed of the engine, and hence a predetermined constant advance movement of the tractor.

It will be noted that all of the working 5 parts of the governor and of the distributor are compactly assembled and all inclosed and protected from the elements.

What I claim is:

1. The combination with a tractor having 10 an internal combustion engine, of a throttle valve for controlling the fuel supply thereto, of an upright governor shaft driven from a running part of the engine, a centrifugal governor carried by said shaft, a lever subject to 15 said governor, a spring acting directly upon one side of said lever, a casing inclosing said shaft, said governor and said spring pressed lever, and an operating rod connected to said throttle valve and extending into said governor 20 casing and provided with a connection therein to said spring pressed lever whereby said throttle valve will be automatically operated from said governor.

2. The combination with a tractor having 25 an internal combustion engine and a throttle valve for controlling the fuel supply thereto, of a governor casing secured to the front of the engine, an upright governor shaft working in said casing and provided with weight- 30 ed levers rotatable therewith and working within said casing, means for driving said shaft from a running shaft to the engine, a spring pressed lever within and having a lateral arm extending upwardly at one side 35 of said casing arranged to be oscillated by said weighted levers under rotation of said shaft, and a rod extended from said throttle valve into said governor casing and having a connection to said spring-pressed lever 40 whereby said throttle valve will be automatically controlled.

3. The combination with a tractor having an internal combustion engine, of a throttle valve for controlling the fuel supply thereto, 45 of an upright governor shaft driven from a running part of the engine, a centrifugal governor carried by said shaft, a lever having an upwardly extending arm at one side of said shaft subject to said governor a com- 50 pression spring below said arm, a casing including said shaft lever and spring, said governor and said spring pressed lever, an operating rod connected to said throttle valve and extended into said governor casing and 55 provided with a connection therefor to said spring-pressed lever whereby said throttle valve will be automatically operated from said governor, and a current distributor having a cup-like casing detachably mounted di- 60 rectly on the upper end of said upright shaft, said distributor casing supporting the relatively fixed contacts of the distributor, and the upper end of said shaft carrying the movable element of said distributor.

65 4. The combination with a tractor having

an internal combustion engine and a throttle valve for controlling the fuel supply thereto, of a governor casing secured to the front of the engine, an upright governor shaft working in said casing and provided with weight- 70 ed levers rotatable therewith and working within said casing, a plate pivoted to said levers above the same, means for driving said shaft from a running shaft to the engine, a lever pivoted at one side of said shaft 75 having its inner end bearing on said plate and an upwardly extending arm at its other end substantially parallel to said shaft, a compression spring pressing upwardly on said arm, a rod extended from said throttle 80 valve into said governor casing and having a connection to said spring-pressed lever whereby said throttle valve will be automatically controlled, and a current distributor having a cup-like casing detachably mounted directly on the upper end of said upright shaft, said distributor casing supporting the relatively fixed contacts of the distributor 85 and the upper end of said shaft carrying the movable element of said distributor.

5. The combination with a tractor having an internal combustion engine, of a throttle valve for controlling the fuel supply thereto, of an upright governor shaft driven from a running part of the engine, a centrifugal 90 governor carried by said shaft, a spring-pressed lever subject to said governor, a casing including said shaft, said governor and said spring-pressed lever, an operating rod connected to said throttle valve and extended 95 into said governor casing and provided with a connection therefor to said spring-pressed lever whereby said throttle valve will be automatically operated from said governor, and a current distributor having a cup-like casing detachably mounted directly on the upper end of said upright shaft, said distributor casing supporting the relatively fixed contacts of the distributor, and the upper 100 end of said shaft carrying the movable element of said distributor, the said casing being formed with an oil cup directly below said distributor and having a thrust bearing for said shaft located in the bottom of said oil cup.

6. The combination with a tractor having an internal combustion engine, of a throttle valve for controlling the fuel supply thereto, of an upright governor shaft driven from a running part of the engine, a centrifugal governor carried by said shaft, a spring-pressed lever subject to said governor, a casing including said shaft, said governor and said spring-pressed lever, an operating rod connected to said throttle valve 120 and extended into said governor casing and provided with a connection therefor to said spring-pressed lever whereby said throttle valve will be automatically operated from said governor, a current distributor having a 125

130

cup-like casing detachably mounted directly on the upper end of said upright shaft, said distributor casing supporting the relatively fixed contacts of the distributor, and the upper end of said shaft carrying the movable elements of said distributor, the said casing being formed with an oil cup directly below said distributor and having a thrust bearing for said shaft located in the bottom of said

oil cup, and an oil delivery tube extending 10 from said oil cup downward into said governor casing and toward said upright shaft.

In testimony whereof I affix my signature in presence of two witnesses.

GEORGE E. CANFIELD.
